DESIGN FOR A PIPE LINE CLEANER

Sydney S. Smith, Scarsdale, N. Y.

Application December 16, 1941, Serial No. 104,659

Term of patent 14 years

To all whom it may concern:

Be it known that I, Sydney S. Smith, a citizen of the United States and a resident of Scarsdale, county of Westchester, State of New York, have invented a new, original, and ornamental Design for Pipe Line Cleaners, of which the following is a specification, reference being had to the accompanying drawing, forming a part thereof.

Figure I is a side elevation of a pipe line cleaner, showing my new design.

Figure II is an end elevation looking towards the front of the pipe line cleaner shown in Figure I.

Figure III is an end elevation looking towards the rear of the pipe line cleaner shown in Figure I.

I claim:

The ornamental design for a pipe line cleaner, as shown.

SYDNEY S. SMITH.
